UNITED STATES PATENT OFFICE

JOHN S. SELLON, OF HATTON GARDENS, COUNTY OF MIDDLESEX, ENGLAND,
ASSIGNOR TO THE ELECTRICAL ACCUMULATOR COMPANY, OF NEW YORK.

AUTOMATIC SWITCH FOR SECONDARY BATTERIES.

SPECIFICATION forming part of Letters Patent No. 392,826, dated November 13, 1883.

Application filed August 30, 1887. Serial No. 248,260. (No model.) Patented in England January 13, 1883, No. 217; in France June 29, 1883, No. 156,156, and in Germany July 17, 1883, No. 27,868.

To all whom it may concern:

Be it known that I, JOHN SCUDAMORE SELLON, a subject of the Queen of Great Britain and Ireland, and a resident of Hatton Gardens, 5 in the county of Middlesex, England, have invented certain new and useful Improvements in Automatic Switches for Secondary Batteries, (for which I have obtained Letters Patent in Great Britain No. 217, dated January 10 13, 1883,) of which the following is a specification.

My invention relates to an automatic switch 15 designed to preserve a uniform electro-motive force in the current furnished by a storage-battery or accumulator.

My invention consists of an electro-magnetic or other suitably-constructed switch, which can be actuated by the outgoing current when such current falls below a given electro-motive force, so as to cause the magnet or magnets to switch in one or more accumulators from time to time as may be required for the purpose of maintaining a constant or practically-constant electro-motive force.

I provide a switch consisting of a pivoted radial arm in position to make contact with a series of radially-disposed contact-points. Said contact-points are connected to a series of tap-wires, each of the tap-wires in succession being connected to a point in the series of cells in advance of the one immediately preceding. The switch-arm is operated by a ratchet and pawl, producing a step-by-step motion. This pawl is operated by an electro-magnet when said magnet is introduced into the working-circuit. A second magnet is normally in the working-circuit, and operates by virtue of variations in the electro-motive force to make and break a short circuit round the first-named magnet, so that when the electro-motive force falls below a predetermined point the short circuit round the first magnet is broken and said magnet is operated to change the position of the switch-arm.

I will now describe my invention by reference to the accompanying drawing.

S is the automatic switch.

s² is an arm pivoted at s³, as is the ratchet-wheel s'. Arm s² is in position to make con-

tact with a series of radially-disposed contacts, 50 c' to c². c² is connected to one terminal of the battery A. c² is connected by a tap-wire to the next cell, c' to the next, and so on, each tap-wire in succession being connected one cell farther from the terminal. The opposite terminal of the battery is connected to the main lead 1. Main lead 2 is connected to the arm s². In the working-circuit, consisting of leads 55 1 and 2, are translating devices, as lamps L.

M is a coarse-wire electro-magnet connected 60 in the main lead 2. Upon the free end of its armature-bar a is a pawl, B, operating the ratchet-wheel s'. N is a fine-wire electro-magnet of high resistance located between the main leads 1 and 2. It is operated by variations in 65 the potential between said leads, and when the electro-motive force is at a predetermined height its armature K is attracted, closing a short circuit, 70 3 4, at the contact-points D D' round electro-magnet M, which is thus practically removed from circuit.

Normally the parts are in the position shown and the required electro-motive force is flowing in the working-circuit. If, now, the electro-motive force drops below the predetermined point, magnet N releases its armature K, circuit 75 3 4 is broken at D D', and current flows in magnet M, which attracts its armature, operating pawl B to move ratchet s' one step ahead and carrying arm s² from contact c² 80 to contact c', thus introducing an additional cell, which adds its electro-motive force to that of the other cells and causes magnet N to again attract its armature K, closing points D D' and cutting magnet M out of circuit. This operation is repeated as often as the electro-motive force drops, until the entire number of cells are included, when the battery is to be recharged.

What I claim, and desire to secure by Letters Patent, is—

1. The combination of two or more cells of secondary battery, a switch consisting of two or more fixed contact-points connected at different points in the said battery, respectively, 95 and a movable contact operated by an electro-magnet in the working-circuit, with a second electro-magnet operated by variations in the

electro-motive force to make and break a short circuit around the first-named magnet.

2. The combination of a series of cells of secondary battery, a switch consisting of two or more fixed contact-points in the said series of cells, respectively, a movable contact forming the terminal of a main lead, an electro-magnet having a coarse-wire winding located in a main lead and controlling said movable contact, and an electro-magnet having a fine-wire winding located in a branch circuit in parallel with a series of translating devices, as lamps, and a pair of contact-points controlled by said magnet respectively connected to the main lead on opposite sides of the first-named magnet.

3. The combination of a series of cells of secondary battery, a working-circuit therefor containing a series of translating devices, a series of fixed contact-points, each electrically

connected to a point in said circuit between a different pair of cells, a movable contact in position to connect with said series of fixed contacts forming one terminal of the divided working-circuit, a step - by - step mechanism for changing the position of said movable contact, an electro-magnet having a coarse-wire winding, and an electro-magnet having a fine-wire winding, both located in the working-circuit and co-operating to control said step-by-step mechanism and change the position of the movable contact, substantially as described.

Signed at London, in the county of Middlesex, this 13th day of August, A. D. 1887.

JOHN S. SELLON.
